MACHINE TO CUT OR TRIM ASPHALT ROADS

James T. Clamp, Miami, Fla.

Application May 27, 1938, Serial No. 210,474

5 Claims. (Cl. 262—8)

My invention is a machine for trimming or cutting the edge of asphalt roads.

As is well known, road beds are now made by mixing in place or upon the road sand and asphalt, with a suitable solvent. This asphalt and sand mix is properly spread or leveled upon the road and is then rolled. It is necessary to cut or trim the edges of the road bed thus produced. This trimming has heretofore been done by hand, and before the mix has become completely hardened by the evaporation of the solvent, whereby the cutting is rendered easier. As far as I am aware, no wheeled machine has been used for this purpose, as a machine which would cut or trim the edge of the partly hardened road bed would be so heavy that it would damage or mark the surface of the road bed. This hand trimming is time consuming and expensive.

In accordance with my invention, I have provided a cutting machine which is mounted upon the roller which is employed to roll the sand and asphalt mix, before the same has completely hardened. This machine is so constructed that its cutter may be shifted to an elevation above the surface of the road bed, and after the surface has been properly rolled by the roller, the machine is adjusted to bring the cutter into engagement with the road bed to cut or trim the edge of the same. My machine will cut or trim the edge in a straight line, and the cutting is accomplished quickly thereby effecting considerable saving in the cost of trimming. The presence of my machine applied to the roller does not interfere with the normal action of the roller in rolling the road bed, and the roller may be employed to propel my machine, without scarring or injuring the surface of the road bed.

In the accompanying drawings forming a part of this application and in which like numerals are employed to designate like parts throughout the same:

Figure 1 is a side elevation of a trimming machine embodying my invention.

Figure 2 is a plan view of the same.

Figure 3 is an end elevation of the same, and, Figure 4 is a perspective view of the same.

In the drawings wherein for the purpose of illustration is shown a preferred embodiment of my invention, the numeral 10 designates a power driven roller as a whole. This roller is preferably of the two wheel type and is generally known as a tandem roller. The roller comprises a rear wheel 11 and a horizontal frame 12, having upper and lower horizontal flanges 13 and 14. The forward portion of the roller includ-

ing the front wheel is not shown, as the construction of such rollers is well known.

The machine embodying my invention comprises a generally horizontal vertically swinging frame 15. This frame is generally triangular and comprises a beam 16, preferably formed of an angle iron, the horizontal web of which is cut away at 17, providing a vertical web extension 18, which is pivotally mounted upon the side of the frame 12, spaced from the flanges 13 and 14, by means of a bolt 19. The frame 15 further includes a diagonal beam 20, preferably formed of two assembled angle irons 21 and 22 having their vertical webs 23 arranged innermost and in engagement with each other and secured together by bolts 24 and also by welding. The horizontal web of the angle iron 21 is cut away near one end, as shown at 25, affording a vertical web extension 26, and the horizontal web of the angle iron 22, near one end, is cut away as shown at 27 to provide a vertical web extension 28, these vertical web extensions engaging each other and being pivotally connected with the opposite side of the frame 12 by means of a bolt 29. The vertical web extensions 26 and 28 are arranged in the same manner with respect to the flanges 13 and 14, as shown in connection with the vertical web extension 18, Figure 1. The opposite ends of the angle irons 21 and 22 overlap the rear end of the angle iron 16, and the horizontal webs of the angle irons 21 and 22 are arranged upon the horizontal web of the angle iron 16 and are welded or otherwise rigidly secured thereto. The vertical web of the angle iron 22 may terminate at the vertical web 35 of the angle iron 16 while the vertical web of the angle iron 21, at its free end, is split from the horizontal web and is bent into a longitudinal extension 30, which may be welded to the vertical web of the angle iron 16. A triangular 40 stiff metal plate 31 is arranged beneath the beams 16 and 20, at the rear end or apex of the triangular frame and is welded or otherwise rigidly secured to the horizontal webs of these beams. This triangular plate 31 has its rear apex extending rearwardly beyond the frame 15. This triangular plate serves as an extension for the triangular frame 15. The triangular frame, with the transverse end of the frame 12, produces a triangular structure, having its side or base extending parallel with the longitudinal axis of the roller and its direction of travel. The arrangement is strong and is rigid against longitudinal and lateral displacements. The tri-

angular frame 15 is adapted to be raised and lowered, by a swinging movement.

Means are provided to raise and lower the frame 15, comprising a relatively stationary supporting structure or support. This supporting structure comprises a main vertical post or upright 32, preferably formed of two assembled angle irons 33, having corresponding webs 34 arranged in engagement with a vertical plate 35, to which they are welded or otherwise secured. Lower horizontal beams 36 and 37, preferably formed of angle irons, converge rearwardly, and have their rear ends rigidly secured to the opposite sides of the angle irons 33 of the vertical post, by welding or the like. Upper inclined rearwardly converging beams 38 and 39 have their ends rigidly secured to the opposite sides of the angle irons 33 by welding or the like. The forward ends of the beams 36 and 37 are rigidly secured to the lower flange 14 of the frame 12 by bolts 41, and the rear ends of the beams 38 and 39 are secured to the upper flange 13 by the bolts 41. The numeral 42 designates an intermediate brace, formed of an angle iron or the like and this brace inclines upwardly in a rearwardly direction. The rear end of this brace enters the vertical post 32 and engages the webs 34 and may be secured thereto by welding and also by means of bolts 43. The forward end of the intermediate inclined brace 42 is secured to the horizontal web 14 by bolts 44 or the like. A second intermediate brace 45 is provided, which inclines upwardly in a rearward direction and also laterally toward the side of the roller. The brace 45 is preferably formed of an angle iron, the forward end 46 of which may be welded to the plate 35, at its lower end, and also secured thereto by the bolts 43. At its upper end, the brace 45 has a bearing 46' secured thereto by bolts 47 or the like.

Rigidly mounted upon one side of the post 32, by any suitable means, and preferably beneath the upper end of the brace 38 is gearing 48, comprising a horizontal worm 49 engaging and driving a vertical worm wheel 50, rigidly mounted upon a horizontal shaft 51, to turn the same. The shaft 51 has a crank or arm 52 rigidly mounted thereon. The worm 49 is formed upon a horizontal shaft 53, the rear end of which is journaled in the bearing 46' and carries a hand wheel 54. Pivotaly connected with the rear end of the crank or arm 51, at 55 is a depending link 56, pivotaly connected at its lower end as at 57, with vertical plates 58 and 59, in turn secured to beams 16 at its rear end by a bolt 60 or other suitable means.

The triangular plate 31 has its rear end or apex preferably inclined upwardly slightly in a longitudinal direction and also in a transverse direction and an arm 61 is rigidly secured thereto by bolts 62 or the like. This arm is equipped with a sleeve or bearing 63, rotatably receiving the shaft 64 of a rotary cutter 65, which is circular and of the plow disk type. The arrangement is such that the face or surface of the disk cutter is preferably disposed at an angle of 11° 10' with respect to the vertical and 21° 00' with respect to the horizontal or longitudinal axis of the roller or the axis parallel to the direction of travel of the roller. The disk cutter converges forwardly with respect to the frame 15, as shown. The disk cutter is rotatable with respect to the bearing 63, as is obvious.

In operation, the sand and asphalt with the suitable solvent may be mixed upon the road and

after being suitably laid or spread thereon, the roller 10 is employed to roll the surface. During the first of this rolling action, the rotary disk cutter 65 is held at an elevation above the road bed so that it will not cut the surface being laid. 5 This is effected by turning the hand wheel 54, which operates through the gearing 48, to swing arm 52 upwardly, elevating link 56, and swinging frame 15 upwardly. After the rolling has reached a desired stage at which the edge of the 10 surface or road bed should be trimmed, the hand wheel 54 is turned to lower the frame 15, and the rotary disk cutter 65 is moved downwardly to a proper lowered elevation, and will cut through the road bed, at the edge thereof, by driving the 15 roller along the road bed, at the edge thereof, the rotary disk cutter may trim the edge in a straight line, or in a curved line at curves in the road. The cutter will trim the edge evenly and quickly, and since the cutting machine is applied to the 20 roller, there is no separate support engaging the road bed which would mar or injure the same. By having the diagonal side of the supporting frame 15 arranged rearmost, as shown, a space is provided for the operator walking upon the 25 road bed. The construction is also strong against lateral strain and shortens up the attachment. The operator is enabled to walk near the disc cutter 65 inwardly of the same and may look down upon the same to accurately observe the 30 work being cut. The hand wheel 54 is located near and upon the inner side of the disc cutter in convenient reach of the operator.

While I have shown my machine as applied to and supported by a roller, the invention is not 35 necessarily restricted to this arrangement, as the machine may be mounted on other supporting means. The machine may also be used for trimming old road beds.

It is to be understood that the form of my in- 40 vention herewith shown and described is to be taken as a preferred example of the same and that various changes may be made in the shape, size and arrangement of parts, without departing from the spirit of my invention or the scope 45 of the subjoined claims.

Having thus described my invention, I claim:

1. In a machine for trimming a road bed, the combination with a wheeled support, of a generally horizontal triangular supporting frame ar- 50 ranged at the rear end of the wheeled support and pivotaly connected therewith to swing vertically and having its base arranged adjacent to one side of the wheeled support, a rotary disk cutter disposed near and outwardly of the base 55 of the supporting frame, means to mount the disk cutter upon the supporting frame, a relatively stationary supporting structure including an up- standing post arranged rearwardly of the wheeled frame, lower rearwardly converging 60 beams secured to the lower end of the post and to the rear end of the wheeled support, upper rearwardly and upwardly converging beams secured to the upper end of the post and to the end of the wheeled support, an intermediate brace in- 65 clined upwardly in a rearward direction and secured to the lower portion of the post and to the rear end of the wheeled frame, gearing mounted upon the post, means connecting the gearing and the vertically swinging supporting frame, and 70 means to operate the gearing.

2. In a machine for trimming a road bed, the combination with a wheeled support, of a generally horizontal triangular supporting frame ar- ranged at the rear end of the wheeled support 75

and pivotally connected therewith to swing vertically and having its base arranged adjacent to one side of the wheeled support, a rotary disk cutter disposed near and outwardly of the base 5 of the supporting frame, means to mount the disk cutter upon the supporting frame, a relatively stationary supporting structure including an upstanding post arranged rearwardly of the wheeled frame, lower rearwardly converging 10 beams secured to the lower end of the post and to the rear end of the wheeled support, upper rearwardly and upwardly converging beams secured to the upper end of the post and to the end of the wheeled support, an intermediate brace inclined upwardly in a rearward direction and secured 15 to the lower portion of the post and to the rear end of the wheeled support, gearing mounted upon the post, a crank driven by the gearing, a link pivotally connecting the crank and the supporting frame, a rearwardly extending shaft 20 to operate the gearing, an upwardly inclined brace secured to the lower portion of the post and having a bearing receiving the rear end of the shaft, and a wheel mounted upon the shaft to turn it.

3. In a machine for trimming a road bed, the combination with a wheeled support, of a generally horizontal triangular supporting frame arranged at and extending beyond one end of the 30 wheeled support and pivotally connected with the wheeled support to swing generally vertically, the triangular supporting frame having its base arranged adjacent to one side of the wheeled support and its diagonal side remote from the rear 35 end of the wheeled support, a rotary disk cutter disposed near and outwardly of the base of the triangular supporting frame and mounted upon the supporting frame, the rotary disk cutter being rotated only by engagement with the road 40 while moving with the wheeled support, the disk cutter being inclined horizontally in a forward direction toward the road bed and also inclined vertically in a downward direction from the road

bed and adjustable means to lower the supporting frame and to positively hold the same in the lowered adjusted position against upward movement, said adjusting means including a manually operated element disposed near the diagonal 5 side.

4. In a machine for trimming a road bed, the combination with a wheeled support, of a generally horizontal triangular supporting frame extending beyond one end of the wheeled support 10 and pivotally connected with the wheeled support to swing generally vertically, the triangular supporting frame having its base arranged adjacent to one side of the wheeled support and its diagonal side arranged remote from the rear end 15 of the wheeled support, a rotary disk cutter mounted upon the triangular supporting frame and disposed near the base of the supporting frame, adjustable means to lower the supporting frame and to positively hold the same in the lowered adjusted position against upward movement, and a manually operated element to actuate the adjustable means and disposed near the diagonal side to be conveniently grasped by an operator walking on the road bed at the rear of 20 the supporting frame.

5. In a machine for trimming a road bed, the combination with a wheeled support, of a generally horizontal supporting frame pivotally mounted upon the wheeled frame to swing generally vertically, a rotary disk cutter mounted upon the supporting frame, a relatively stationary supporting unit mounted upon the wheeled frame, a generally horizontal shaft extending near the rear end of the supporting frame, a 30 worm driven by the shaft, a worm wheel mounted upon the supporting unit and engaging the worm, a vertically swinging arm moved by the worm wheel, a link pivotally connecting the arm and supporting frame, and manually operated 35 element mounted upon the rear end of the shaft.

JAMES T. CLAMP.
